UNITED STATES PATENT OFFICE.

LOUIE H. OBERREICH, OF INDIANAPOLIS, INDIANA.

CARBURETER.

1,328,844.

Specification of Letters Patent.

Patented Jan. 27, 1920.

Application filed October 4, 1916. Serial No. 123,790.

To all whom it may concern:

Be it known that I, LOUIE H. OBERREICH, a citizen of the United States, residing at Indianapolis, in the county of Marion and State of Indiana, have invented a new and useful Carbureter, of which the following is a specification.

It is the object of my invention to produce a more efficient carbureting action for obtaining an explosive mixture for internal combustion engines, to produce a more intimate mixture of the fuel and air and a finer division of the fuel, to vaporize the fuel by the action of heat, to crack the fuel so as to obtain permanent gases, to obtain the heating action on the fuel immediately upon the starting of the engine, to produce practical self-regulation; and to provide a carbureting arrangement which will do this with lower grades of fuel such as kerosene and crude oil.

In carrying out my invention, I use a small portion of the exhaust gases, under the exhaust pressure, to atomize and at the same time heat the fuel, and discharge this mixture of atomized and heated fuel with the small quantity of exhaust gases into the intake passage to produce the explosive mixture. The slight admixture of burned gases from the exhaust does not vitiate the explosive mixture materially, and is much more than offset by the heat and atomizing action thereof. I may also atomize water with the fuel, when the quality of the fuel makes that desirable, though some moisture is provided by the exhaust gases used for atomizing, by reason of the production of water in the engine explosions.

The single figure of the accompanying drawing illustrates my invention somewhat diagrammatically.

The engine 10 is an internal combustion engine of any type, shown as a multi-cylinder engine having an intake manifold 11 and an exhaust manifold 12 suitably connected to the several engine cylinders. The air supply for the intake manifold is supplied through the mixing tube 13, which in turn conveniently receives its supply from an air-heating jacket 14 surrounding the exhaust manifold 12, as is now common practice.

In addition to its main outlet through the muffler, the exhaust manifold has a lateral outlet 15, of sufficient size to prevent clog-

ging, which lateral outlet leads to a contracted atomizer orifice 16 discharging into an atomizing chamber 17 across a fuel supply nozzle 18 which is supplied with fuel from a float chamber 19 into which fuel is supplied to maintain a constant level in any usual manner, and the atomizing chamber is connected by a pipe 20 to a nozzle 21 located within the mixing tube 13, conveniently within a Venturi tube 22 within such mix-

ing tube. By this construction, part of the exhaust gases from the exhaust manifold 12 is diverted through the lateral outlet opening 15 and discharged with considerable velocity through the atomizer orifice 16, so as to atomize fuel from the fuel nozzle 18 into the chamber 17. This produces not only a very fine atomization of the fuel, but by reason of the heat of the exhaust gases produces an effective vaporization of the fuel, even though it is of low grade. The heat also produces some cracking of the fuel into permanent gases. This heating action takes place instantaneously after the first explosion, without waiting for the entire engine to become heated. This heating effect is augmented after a short time, by reason of the heating of the walls of the atomizer chamber 17, and the striking of the atomized fuel against such walls opposite the atomizer orifice 16. Although the exhaust gases are very hot, there is no combustion in the atomizer chamber 17, because of the inert character of such exhaust gases, whereby they will not support combustion of the fuel. This mixture of hot inert gases and vaporized and atomized and somewhat cracked fuel is carried through the pipe 20 and discharged from the nozzle 21 into the stream of air passing upward through the mixing tube 13 and the Venturi tube 22 to the intake manifold 11, and mixes with such air to produce an exceedingly efficient explosive mixture, because of the advantages obtained by discharging the fuel into the air in the condition mentioned. The slight admixture of the inert burned gases to this explosive mixture produces practically no injurious effect on its explosive qualities, and any small effect there may be is more than offset by the benefits derived from the action of such exhaust gases in atomizing, vaporizing, and cracking the fuel.

In using low grade fuels, it has been

- found desirable to provide some moisture in the explosive mixture. In some cases sufficient moisture is provided by the burned gases, which contain a small percentage of moisture on account of the water which is formed by the explosion. If this water is not enough, additional water may be supplied from a water nozzle 25 placed beside the fuel nozzle 18 and supplied with water from a float chamber 26 in which a constant water level is maintained in any suitable manner. The water from the nozzle 25 is atomized and vaporized along with the fuel from the fuel nozzle 18.
- 15 In order to prevent the possibility of actual flames from the exhaust manifold entering the atomizer chamber 17 and striking the fuel therein, I preferably provide in the passageway from the lateral opening 15 to the atomizer orifice 16 a chamber 30, in which the exhaust gases are cooled somewhat and any flame is allowed to dissipate itself. This chamber 30 has a baffle plate 31 near its outlet end, to prevent any flames 20 from passing directly through the chamber from the atomizer orifice 16.
- 25

Inasmuch as the cracking of the fuel in the atomizer chamber 17 produces permanent gases, I may provide a storage chamber 30 35 in the pipe 20 for retaining such permanent gases (though mixed with some of the inert burned gases) when the engine is stopped, so that such permanent gases may constitute the first discharge from the nozzle 21 when the engine is next started. This facilitates starting. If desired, shut-off valves 36 and 37 may be provided in the pipe 20 on the two sides of the storage chamber 35 for isolating such chamber to prevent 40 the escape of such permanent gases while the engine is at rest.

Also in order to facilitate starting, a choker valve 40 may be provided in the supply pipe leading to the mixture tube 13, for cutting 45 down or shutting off the supply of air. By reason of this, the explosive mixture supplied to the manifold 11 is enriched, not only by the reduction in the amount of air, but by the fact that if the explosive mixture 50 goes through the engine without exploding, as frequently happens at starting, a certain part of this explosive mixture will be carried through the lateral outlet 15 and atomizer orifice 16 to atomize more fuel and carry 55 it through the pipe 20 and nozzle 21 into the explosive mixture again, so that there is a cycle through which part of the explosive mixture travels with constant enrichment until explosion occurs.

60 The speed of the engine is controlled by a throttle valve 41, in the usual manner, this throttle being shown as located above the nozzle 21 and Venturi tube 22 in the mixture tube 13. The manipulation of the 65 throttle 41, however, affects but very

slightly, if at all, the character of the explosive mixture, for as the speed of the engine increases the back pressure in the exhaust manifold 12 also increases and a greater amount of the burned gases passes through the lateral outlet 15 and atomizes more fuel from the fuel nozzle 16 for discharge from the nozzle 21 into the air passing upward through the mixture tube 13. However, a regulating valve 42 is provided in the connection from the lateral outlet 15 and the atomizer orifice 16 to regulate the amount of burned gases supplied to such orifice, should that become necessary. The various valves referred to may be operated in any 70 convenient manner, as by push rods leading to the dash board in the ordinary way. Suitable valves 43 and 44 may also be provided for regulating the flow from the fuel and water nozzles 18 and 25.

75 When low grade fuel is used, it is sometimes desirable to provide a priming tank 45 of higher grade fuel, which can be carried from such tank 45 through a pipe 46 into the supply passage at any suitable point, such 80 as into the atomizing chamber 17, for further facilitating starting.

85 If desired, the lateral opening 15 may have some suitable deflector arrangement such as a baffle plate 50 to make sure that 90 part of the exhaust gases pass from the exhaust manifold through such lateral opening; though ordinarily the back pressure from the muffler is sufficient to accomplish this result.

95 I claim as my invention:

1. In combination, an internal combustion engine having main intake and exhaust passages, a branch connection from the exhaust passage to the intake passage for carrying part of the exhaust gases from the exhaust passage to the intake passage, and a fuel nozzle across which the exhaust gases traveling such branch connection are discharged to atomize the fuel, said branch connection being provided with an enlargement in which said fuel nozzle is located to provide an atomizer chamber, and with a second enlargement between said first enlargement and the exhaust passage for dissipating any 105 flames in the exhaust gases before such flames reach said first enlargement.

110 2. In combination, an internal combustion engine having main intake and exhaust passages, a branch connection from the exhaust passage to the intake passage for carrying part of the exhaust gases from the exhaust passage to the intake passage, and a fuel nozzle across which the exhaust gases traveling such branch connection are discharged to atomize the fuel, said branch connection being provided with an enlargement in which said fuel nozzle is located to provide an atomizer chamber, and with a second enlargement between said first enlargement 115 120 125 130

and the exhaust passage for dissipating any flames in the exhaust gases before such flames reach said first enlargement, said second enlargement being provided with a baffle plate 5 for preventing the passage of exhaust gases directly through it.

3. In combination, an internal combustion engine having intake and exhaust passages, a branch connection from the exhaust 10 passage to the intake passage for carrying part of the exhaust gases from the exhaust passage to the intake passage, and fuel and water nozzles across which the exhaust gases traveling such branch connection are discharged to atomize the fuel and water.

4. In combination, an internal combustion engine having intake and exhaust passages, a branch connection from the exhaust 20 passage to the intake passage for carrying part of the exhaust gases from the exhaust passage to the intake passage, a fuel nozzle across which the exhaust gases traveling such branch connection are discharged to atomize the fuel, and a valve in the intake 25 passage on the intake side of where such branch connection discharges thereinto.

5. In combination, an internal combustion engine having intake and exhaust passages, a branch connection from the exhaust 30 passage to the intake passage for carrying part of the exhaust gases from the exhaust passage to the intake passage, a fuel nozzle

across which the exhaust gases traveling such branch connection are discharged to atomize the fuel, and a Venturi tube in said 35 intake passage at the point where such branch connection discharges thereinto.

6. In combination, an internal combustion engine having main intake and exhaust 40 passages, a branch connection from the exhaust passage to the intake passage for carrying part of the exhaust gases from the exhaust 45 passage to the intake passage, and a fuel nozzle across which the exhaust gases traveling such branch connection are discharged to atomize the fuel, said branch connection being provided with an enlargement between said nozzle and the exhaust passage for dissipating any flames in the external 50 passage before such flames reach the nozzle.

7. The method of carbureting air to produce an explosive mixture for an internal combustion engine, which consists in diverting a portion of the exhaust gases from such 55 engine and using it to atomize fuel and water into the air supplied to the intake of the engine.

In testimony whereof I have hereunto set my hand at Indianapolis, Indiana, this second day of October, A. D. one thousand nine hundred and sixteen.

LOUIE H. OBERREICH.
